UNITED STATES PATENT OFFICE.

GEORGE CROSS, OF JEANNETTE, PENNSYLVANIA.

WRENCH.

1,331,956.

Specification of Letters Patent

Patented Feb. 24, 1920.

Application filed October 21, 1919. Serial No. 332,209.

To all whom it may concern:

Be it known that I, GEORGE CROSS, a citizen of the United States, residing at Jeannette, in the county of Westmoreland and 5 State of Pennsylvania, have invented a new and useful Wrench, of which the following is a specification.

This invention relates to new and useful improvements in a ratchet wrench, and 10 more particularly to a device of this character having means for permitting adjustment of the head thereof with relation to the handle, thereby facilitating the use of the wrench in corners, or in locations where 15 the hand room is limited.

A further object of the invention is to provide means for locking the head in such positions of adjustment, whereby the possibility of the head moving with relation to 20 its handle, is absolutely eliminated.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without 30 departing from the spirit of the invention.

Referring to the drawing:—

Figure 1 illustrates a front elevational view of the wrench,

Fig. 2 is a side elevational view the same 35 in an adjusted position;

Fig. 3 is a sectional view of the ratchet head taken on line 4—4 of Fig. 1,

Fig. 4 is a longitudinal sectional view of the same,

Fig. 5 is a side elevational view of the same,

Fig. 6 is a sectional view through the jaw, taken on line 6—6 of Fig. 1.

Fig. 7 is a side elevational view of the same,

Referring to the drawing in detail, the reference character 5 designates the wrench handle, which is bifurcated at one of its ends, the opposite end thereof being provided with an opening 6, which opening is constructed to receive a suitable bar or tool to facilitate the operation of the wrench when the same is used in removing or positioning a nut of a bolt disposed in a vertical 50 plane.

The head 7, is substantially circular in formation, the same being provided with trunnions 8 formed integral with the opposed outer side faces thereof, and which trunnions, are adapted to be positioned 60 within the apertures 9, formed adjacent the end of each of the furcations, to provide bearings for the trunnions 8, whereby the head is capable of free but limited pivotal movement with relation to the handle, thus 65 enabling the head to be adjusted at various angles to meet the requirements of the work to which the same is applied.

Disposed within the handle 5, and extending from a point substantially intermediate 70 the length of the handle, and terminating at a portion between the furcations of the bifurcated end, is a slot 10, which slot is of a width slightly greater than the width of the connecting link 11, which has one of its ends 75 pivotally connected to the head 7, as at 12, whereby the head is capable of free movement with relation to the connecting link 11.

This connecting link 11, is provided with an elongated slot 13, which slot accommodates the bolt 14, which is positioned in suitable registering openings 15, extending through the sides of the handle 5, at a point adjacent the bifurcated end thereof, the connecting link 11, as shown, being disposed 85 within the slot 10.

It will thus be seen that when it becomes necessary to adjust the head 7 with relation to the handle 5, it is only necessary to loosen the thumb nut 16, thereby permitting the 90 connecting link 11 to move freely within the slot 10, until the proper adjustment is made, whereupon the thumb nut 16 is again rotated to clamp the walls of the slot 10 into close engagement with the connecting link 95 11, with the result that the head is secured in such positions of adjustment, against displacement under ordinary strain.

Within the head 7, and disposed on one of the side walls thereof is an opening 17, 100 which opening is formed to accommodate the coiled spring 18, which spring provides a seat for the pin 19, which is of a length to extend beyond the inner wall of the head 7, to contact with the notches 20, formed in 105 the jaw 21, of the wrench.

From the foregoing it is obvious that due to the construction of the outer surface of the jaw 21, the jaw is permitted to rotate within the head, in one direction, but re- 110

stricted from such rotary movement in the opposite direction, thus providing the ratchet type of wrench.

This jaw 21 is provided with a plurality of cut out portions formed in its periphery, which cut out portions provide the shoulders 23', which shoulders coöperate with the pin 19 for preventing rotation of the jaw 21, within the head 7, when the handle is moved in one direction. An annular flange 23 is formed on one of the side faces of the jaw, which annular flange 23, contacts with one of the side faces of the head, to prevent movement of the jaw, laterally, within the head.

The opposite side face of the jaw is provided with a series of cut out portions 24, and a plurality of lugs 25, disposed between the cut out portions, the under side of each of the lugs being beveled as at 26, to correspond to the bevel of the lugs 27, formed on the locking ring 28.

On positioning the locking ring 28, to secure the jaw to the head 7, the lugs 27 are positioned over the cut out portions 24, and rotated until the lugs 27 engage under the lugs 25, whereupon the screw 29 is then positioned within the base of one of the cut out portions, the head of the screw contacting with the jaw 21, and the locking ring 28.

It will thus been seen that the locking ring is now secured to the jaw 21, and the jaw is permitted to rotate in one direction, but prevented from lateral movement within the head 7.

In the operation of the wrench, it will be seen that when the jaw, or head 6 of the wrench, is in the position as disclosed by Fig. 1 of the drawings, the wrench may be used in the well known manner, but in the event that the wrench is to be put to use, for removing or setting a nut, associated with a bolt positioned in a vertical plane, or in places where nuts closely engage a flat surface, the head 7 may be adjusted to a

position as disclosed by Fig. 2 of the drawings, where the handle of the wrench, when the head is adjusted to this position, operates at right angles, to the sides of the head 7.

It may be found desirable to move the handle, at an angle of say 45 degrees, with relation to the head, in the event that the device is to be used in a corner.

Having thus described the invention, what I claim is:

1. In a wrench, a handle having a bifurcated end, an adjustable head supported between the furcations, a clutch jaw supported within the head, a pawl coöperating with the clutch jaw, a link having an elongated slot formed therein, one end of the link having connection with the head, a bolt extending transversely through the handle, and intersecting the slot, said bolt adapted to be positioned within the slot of the connecting link, and means operating on one end of the bolt for securing the connecting link in various positions of adjustment.

2. In a wrench, a handle, an adjustable head disposed adjacent one end of the handle, a connecting link having connection with the head and the handle, for securing the head in various positions of adjustment, a removable ratchet jaw having recesses and lugs formed on one of the surfaces thereof, a pawl coöperating with the ratchet jaw, a locking ring having lugs adapted to engage under the lugs of the ratchet jaw for preventing lateral movement of the jaw with relation to the head, and means for securing the locking ring against rotary movement.

In testimony that I claim the foregoing as my own I have hereto affixed my signature in the presence of two witnesses.

GEORGE CROSS.

Witnesses:

GEORGE F. STEINCE,

JAMES McWILLIAMS.
